UNITED STATES PATENT OFFICE

WILLIAM L. BEAN, OF WEST HAVEN, CONNECTICUT

LOCOMOTIVE-SMOKE-BOX SPARK NETTING

Original application filed June 2, 1925, Serial No. 34,406. Divided and this application filed April 2, 1926. Serial No. 99,417.

This invention relates to locomotive smoke-box spark nettings. The invention will be best understood by reference to the following description, when taken in connection with the accompanying drawings of one specific embodiment thereof, while its scope will be more particularly pointed out in the appended claims.

In the drawings:

10 Fig. 1 is a longitudinal, vertical, sectional view of a locomotive smoke box structure having a spark netting exemplifying the invention;

15 Fig. 2 is a plan of a portion of the deflector which supports the lower edge of the spark netting;

Fig. 3 is a sectional view on an enlarged scale on line 3—3 of Fig. 2;

20 Fig. 4 is a front elevation of the spark netting;

Fig. 5 is a sectional view of an enlarged scale on line 5—5 of Fig. 4;

Fig. 6 is a sectional view on an enlarged scale on line 6—6 of Fig. 4;

25 Fig. 7 is a sectional view on an enlarged scale on line 7—7 of Fig. 4;

Fig. 8 is a sectional view on line 8—8 of Fig. 4;

Fig. 9 is a skeletonized view, illustrating 30 the supports for the deflector and spark netting;

Fig. 10 is a sectional view on line 10—10 of Fig. 9; and

Fig. 11 is a sectional view on an enlarged 35 scale on line 11—11 of Fig. 9.

Referring to the drawings, and to the embodiment of the invention which is selected for exemplification, and having reference at first more particularly to Fig. 1, the smoke-box structure comprises a smoke-box 19, having a circumferential wall 20, which has in its upper portion an opening 21 for the usual stack 22, and in its lower portion an opening 23 for a usual exhaust pipe (not shown), the 40 exhaust from which is directed upward and through the stack, and thereby induces a draft in a well known manner.

The deflector which deflects the gases in a downward direction, and compels them to flow first to the forward end of the smoke-

box and thence in an upward and rearward direction through the spark netting into the path of the exhaust steam toward the stack, will now be described, reference being had at first to Fig. 1.

55 The deflector comprises a rear, generally upright portion, designated generally by the numeral 24, and a lower, generally horizontal portion, herein a plate designated generally by the numeral 25. This plate is conveniently supported at both ends by bars 26, suitably secured to the circumferential wall of the smoke-box, as by rivets 27, said bars presenting inwardly directed flanges 28, on which the plate rests.

60 The spark netting will now be described, reference being had at first to Fig. 4.

65 The netting in the present example comprises left and right portions 29 and 29', a central, upper portion 30, and a central, lower portion 31, the latter constituting a door. The sections 29 and 29' lie in one plane, while the section 30 lies in a plane parallel thereto, and has margins which overlie the margins of the sections 29 and 29'. This is clearly 70 apparent from an inspection of Fig. 6, wherein the overlying margins of the sections 29 and 30 are received in oppositely facing grooves 32 and 33, presented by a bar 34. This bar may be secured to the section 29, 75 as by welding at 35. A similar bar 34', arranged in like manner, connects the overlying edges of the section 30 and the section 29'. This construction provides a joint, which prevents any possibility of sparks 80 passing through the joint, while at the same time, it permits the intermediate section 30 to be removed quickly and conveniently by sliding the same in a downward direction out of the grooves presented by the bars.

85 The section 31 in the present example lies in the same plane as the section 30, and has margins which overlie corresponding margins of the sections 29 and 29', as will be evident from an examination of Fig. 8. These 90 overlying margins are conveniently secured to each other, as by pins 36, extending through the overlying margins, and riveted to a bar 37, which is secured to the section 29 as by welding at 38. Each pin projects 95 100

through the door section 31, and is provided with a washer 39, which cooperates with a locking pin 40 to hold the door section in place. Similar fastenings secure the door section to the section 29'.
5

The door section 31 lies in the same plane as the section 30. This is well illustrated in Fig. 7, which shows these two sections presented edge to edge. These edges are suitably secured to each other, as by pins 41, which extend through the section 31, and are riveted to a bar 42, suitably secured as by welding at 43 to the section 30. Washers 44 encircling the pins 41 are held in place by
10 keys 45, extending through the pins 41.

The spark netting sections 29, 29' and 30, together, present a circular margin, which is received in a groove 46, (see Fig. 9), provided in a bar 47 conveniently secured to the
15 circumferential wall of the smoke-box, as by rivets 48. Inasmuch as the intermediate section 30 of the spark netting lies in a different plane from the sections 29 and 30, the groove 46 is provided with an offset portion
20 49 (see Fig. 10). The described construction therefore provides a tongue and groove joint, having the advantage that it prevents the escape of sparks, yet it does not call for the use of bolts to draw the joint together to
25 make it tight. Moreover, the sections 29, 29' and 30 of the spark netting can be inserted into and withdrawn from the groove 46 very conveniently.

The lower margins of the sections 29 and
30, as well as the lower margin of the section 31, are received in a groove 50 (see Figs. 2 and 3) between angle bars 51 and 52, secured
35 to the plate 25. Inasmuch as the lower section 31 lies in a different plane from the sections 29 and 29', this groove has an offset portion 53 (see Fig. 2), to receive the door section.
40

The spark netting structure, as thus far described, has its marginal portion throughout
45 received in grooves, which securely hold it in place, but to prevent any possibility of the front edge of the plate 25 sagging or warping, due to its exposure to the hot gases, the spark netting may be used as a means of support for the plate. To this end, the upper corners of the spark netting sections 29 and 29' are secured in the groove 46 of the bar 47 by pins 54, and the intermediate section is secured by a pin 55 (see Fig. 5), while the
50 lower corners of the plates 29 and 29' are secured to the bars 51 and 52 by pins 56. Thus it is evident that there is no possibility of warping of the parts, which might permit sparks to pass through the joint, while at the
55 same time, the assemblage is such that the door section of the spark netting can be removed with great facility, and if desirable, the remaining sections can be removed and replaced with equal ease.
60

65 This application is a division of my pend-

ing application for locomotive smoke-box structures, Ser. No. 34,406, filed June 2, 1925.

Having thus described one embodiment of the invention, but without limiting myself thereto, what I claim and desire to secure by
70 Letters Patent is:

1. In a smoke-box structure, a spark-netting, comprising two sections which lie in a common plane and a third section which lies in a plane parallel to the other two, and two bars each presenting two oppositely facing grooves which receive adjacent margins of said third section and one of said two sections.
75

2. In a smoke-box structure, a spark-netting, comprising two sections which lie in a common plane and a third section having two margins which overlie margins of said two sections, two bars each presenting two oppositely facing grooves which receive two of
80 said overlying margins, and a fourth section having two margins which overlie said two sections, respectively, and a third margin which is presented edge to edge with a margin of said third section.
85

3. In a smoke-box structure, a spark-netting, comprising two sections which lie in a common plane, a third section having two margins which overlie margins of said two sections, two bars each presenting two oppositely facing grooves which receive two of
90 said overlying margins, and a fourth section having two margins which overlie said two sections, respectively, a third margin which is presented edge to edge with a margin of said 100 third section, and a bar which overlies said edges.
95

4. In a smoke-box structure, a spark-netting, comprising three sections one of which is intermediate the other two, and two bars connecting said sections each of which bars comprises elements providing two oppositely facing grooves, one of which grooves receives an edge of said intermediate section, and the other of which grooves receives the adjacent
105 edge of one of the other sections.
110

5. In a smoke-box structure, a spark-netting, comprising three sections one of which is intermediate the other two, two bars each of which has two oppositely facing grooves, one of which grooves receives an edge of said intermediate section, and the other of which grooves receives the adjacent edge of one of the other sections, and a fourth section normally preventing removal of said intermediate section by movement lengthwise of the grooves in which its said edges are received.
115
120

6. In a smoke-box structure, a spark-netting, comprising three sections, one of which is intermediate the other two and has opposite converging edges, and two bars each of which comprises elements providing two oppositely facing grooves, one of which grooves receives one of said opposite edges,
125 130

and the other of which grooves receives the adjacent edge of one of the other sections.

7. In a smoke-box structure, a deflector, and a spark-netting comprising two sections which lie in a common plane and a third section which lies in a parallel plane, said deflector and sections having tongue and groove connection with each other comprising bars secured to said deflector and providing a groove which receives said netting sections.

8. In a smoke-box structure, a spark-netting comprising two spaced sections which will lie in a common plane and a third section between said spaced sections and lying in a parallel plane, said sections having elements cooperating to form a substantially continuous edge for said netting with an intermediate portion offset from the end portions, and means for mounting said sections in the smoke-box which means presents a correspondingly offset groove for receiving said elements.

In testimony whereof, I have signed my name to this specification.

WILLIAM L. BEAN.
